UNITED STATES PATENT OFFICE.

JOHN A. HEATON, OF PHILADELPHIA, PENNSYLVANIA.

MEMORANDUM CALENDAR.

Application filed January 21, 1925. Serial No. 3,721.

My invention relates to memorandum calendars, and it relates more particularly to a calendar which is so constructed and arranged as to receive and support memorandum slips or cards at desired specific dates.

The object of my invention is to provide a memorandum calendar which will be simple in arrangement and inexpensive in construction, on which the various days are designated in such manner as to require a minimum of space commensurate with the particular use of the calendar, and a further object of my invention is to provide in such a calendar, in connection with the spaces provided for the various days of the year, elongated slots in the front or face member of the calendar structure, which slots are adapted to receive slips of paper or cards upon which notations are made for the purpose of informing the user of various matters to be attended to upon specific dates.

The nature and characteristic features of my invention will be more readily understood from the following description, taken in connection with the accompanying drawings forming part hereof, in which:

Figure 1 is a front elevation of a memorandum calendar embodying the main features of my present invention;

Fig. 2 is a fragmentary elevational view, enlarged, of a portion thereof;

Fig. 3 is a vertical section of the portion of the structure shown in Fig. 2;

Fig. 4 is a view similar to Fig. 3, but illustrating a modified form of construction, this form being particularly adapted for use when the structure is made of sheet metal;

Fig. 5 is a horizontal section of the structure shown in Fig. 4; and

Fig. 6 is a perspective view of a specimen memorandum slip adapted to be used with the calendar.

Referring now more particularly to Figs. 1 to 3 of the drawings, in the particular embodiment of my invention therein shown, 6 is a sheet of suitable material, such as cardboard, sheet metal, celluloid or the like. The face of the sheet 6 has the calendar proper printed thereon, the same being divided by vertical lines 7 into a series of columns, preferably thirteen in number, and further subdivided by means of horizontal lines 8 into thirty-two rows of spaces. Preferably in the central vertical column, in the top space thereof, the year of the calendar

is designated by the proper numerals (1925), and successively in the spaces below the same in said central column are displayed the numerals "1" to "31", to represent the days of the several months.

60

In the other spaces of the top row are designated the various months of the year (Jan., Feb., Mar., etc.), and in the spaces in each vertical column the day of the week corresponding to the particular date is 65 designated (Sun., Mon., Tue., etc.). Likewise, if desired, in each of the spaces provided for specified date there may be provided the proper numeral for designating the total elapsed days of the year.

70

In each of the spaces provided for each day of the year there is provided an elongated slot 9, which is adapted to receive a memorandum slip 10, which may be a folded piece of paper (see Fig. 6) or a card, upon which notations may be made to inform the user of various matters to be attended to upon a particular date, it, of course, being understood that the memorandum slip 10 is inserted in the slot 9 corresponding to such 80 date.

75

In order that the memorandum slips or cards may be inserted without crowding each other, or unduly obscuring the face of the sheet, the sheet 6 is preferably secured 85 at its marginal edges to a framework 11, which serves to hold the sheet 6 away from the surface of the wall or other support upon which the calendar is hung or mounted.

If desired, the back of the structure may be closed by means of a sheet 12, which may also be secured to the framework 11, and for the purpose of hanging the device upon the wall or other support, the sheet 12 at the rear of the device may be provided with 90 tabs 13 extending upward above the top member of the framework and having eyes 14 for mounting the structure upon nails or hooks.

95

When the device is made of sheet metal, the equivalent of the marginal framework may be provided, as shown in Figs. 4 and 5, by bending the metal of the structure over at the top and sides and thence inward as at 15 (see Fig. 5) a sufficient distance to 105 form an adequate support, and likewise the tab portions 13 may be provided by suitably bending a portion of the sheet metal upward, as shown in Fig. 4 of the drawings.

105

It will be seen that by the foregoing arrangement there is provided a memorandum

110

- calendar, which may be inexpensively constructed, in which memorandum slips or cards may be so inserted as to attract the attention of the user to a specified date, and 5
5 which is characterized by being of minimum size for its intended purpose. Furthermore, the spaces for the various dates will not be unduly obscured by the inserted memorandum slips.
- 10 It will be found in practice that a calendar of the peculiar construction and arrangement of the present invention will be useful in many respects; for example, suppose that a note be given on February 17, 15 1925, payable 90 days after date. A memorandum slip is taken and the proper notation made thereon, and reference is then made to the calendar, and it is found that, at the end of that day, 48 days will have 20 elapsed since the first of the year. By simple addition of 90 to this figure, and further reference to the calendar, one finds that the 138th day of the year falls on May 18, 1925, whereupon the memorandum slip with 25 the notation of the note becoming due is inserted in the slot corresponding to that day.
- It will, of course, be understood that additional space may be provided upon the face of the calendar for advertising matter, 30 as in many instances it may be found desirable to use the device of my present invention for advertising purposes, and this may be done without departing from the spirit of my invention.
- 35 Having thus described the nature and characteristic features of my invention, what I claim as new and desire to secure by Letters Patent, is:
1. A memorandum calendar comprising a 40 front sheet having printed on the face thereof vertical and horizontal lines dividing said face into spaces designated for the various days of the year, said sheet having elongated slots extending therethrough, one 45 of said slots being provided for each date designating space, means adapted to hold the same away from the surface upon which

said calendar may be mounted, and sheet-like memorandum slips adapted to be inserted flatwise in the slots in said sheet. 50

2. A memorandum calendar comprising a front sheet having printed on the face thereof vertical and horizontal lines dividing said face into spaces designated for the various days of the year, said sheet having 55 elongated slots extending therethrough, one of said slots being provided for each date designating space, a framework at the marginal edges of said sheet adapted to hold the same away from the surface upon which 60 said calendar may be mounted, tabs extending upward from the top member of said framework, said tabs having eyes for hanging the structure on a wall or other suitable support, a sheet secured on the back 65 of the framework, and sheet-like memorandum slips adapted to be inserted flatwise in the slots in the front sheet.

3. A memorandum calendar comprising a front sheet having printed on the face 70 thereof vertical and horizontal lines dividing said face into vertical and horizontal rows of spaces, the central vertical row having numerals arranged in sequence to indicate days of each month, vertical rows on 75 each side of the central vertical row designating the various days of the respective months, the days of the week of the various days of the respective months being designated in the respective spaces in said vertical rows, each of said months being designated at the top of the respective vertical rows, said sheet being provided with elongated slots extending therethrough, one of 80 said slots being provided for each date 85 designating space, means for supporting said front sheet in spaced relation to the element upon which the calendar is supported and sheet-like memorandum slips adapted to be flatwise inserted in the slots 90 in said sheet.

In testimony whereof, I have hereunto signed my name.

JOHN A. HEATON.
